Primary Examiner — Vy Koenig*Assistant Examiner* — Keith Wilson(74) *Attorney, Agent, or Firm* — Rosenberg, Klein & Lee(57) **CLAIM**

The ornamental design for a shower chair, as shown and described.

DESCRIPTION

FIG. 1 is a perspective view of the shower chair showing my present design;

FIG. 2 is a front view thereof;

FIG. 3 is a rear view thereof;

FIG. 4 is a left elevational view thereof;

FIG. 5 is a right elevational view thereof;

FIG. 6 is a top plan view thereof; and,

FIG. 7 is a bottom plan view thereof.

The broken lines depict portions of the shower chair that form no part of the claimed design.

1 Claim, 7 Drawing Sheets(56)
